UNITED STATES PATENT OFFICE.

FRANK W. SEVERIN, OF CHICAGO, ILLINOIS, ASSIGNOR TO VENN-SEVERIN MACHINE CO., OF CHICAGO, ILLINOIS, A CORPORATION OF ILLINOIS.

GOVERNING MECHANISM FOR OIL ENGINES.

Application filed July 9, 1921. Serial No. 483,628.

The invention relates to the fuel-feed governing mechanism for oil engines of that type in which the suction valve for the fuel-pump is held open for varying periods responsive to the power requirements of the load under control of a governor to regulate the volume of fuel injected into the engine.

One object of the invention is to provide an improved governor mechanism of this type in which no reactive load is imposed on the governor-cam which controls the periods during which the suction valve remains open.

A further object is to provide governor mechanism of this type which is simple in construction and efficient in operation.

Another object of the invention is to provide improved means for varying the spring tension on the governor-arms to regulate the speed of the engine.

Another object is to provide an improved governing mechanism of this type with means for destroying the inertia of the line of oil between the supply tank and the suction valve of the pump.

A still further object is to provide improved means for manually operating the fuel pumps.

The invention consists in the several novel features hereinafter set forth and more particularly defined by claims at the conclusion hereof.

In the drawings: Fig. 1 is a longitudinal section of mechanism embodying the invention. Fig. 2 is a section taken on line 2—2 of Fig. 1, showing the pump-operating cam. Fig. 3 is a section taken on line 3—3 of Fig. 1, showing the suction valve operating cam. Fig. 3^a is a section on line 3^a—3^a of Fig. 1. Fig. 4 is a side elevation of the governor. Fig. 5 is a section taken on line 5—5 of Fig. 4. Fig. 6 is a plan. Fig. 7 is a section taken on line 7—7 of Fig. 1. Fig. 8 is an enlarged detail showing the cams for operating and controlling the suction valve.

The invention is exemplified in mechanism supported in a suitable bracket 10 which is usually mounted on the engine-casing and driven by a hollow shaft 11 which is geared and driven by the crank-shaft of the engine at a rotative speed suitable to the cycle of the engine. The mechanism shown is for a two-cylinder engine, there being a fuel-feed pump and connections for each cylinder of the engine, although it is to be understood that the invention may be applied to single

or any multiple cylinder engines, as well understood in the art. Since the pump and connections for each cylinder are alike in construction, a description of one is deemed sufficient.

Each pump comprises a casing 12 which is secured to frame 10 and is provided with a chamber 17 and a cylinder 13 in which a plunger 14 is slidably mounted. A spring 15 is applied to impart the retractile stroke to the piston, its outer end being held in a head 16 which is secured to the casing opposite cylinder 13. A suction-valve 18 is slidably mounted in a seat 19 which is secured in the casing and is normally closed by a spring 32. Said valve is provided with a suitably grooved stem 20 which is formed to receive oil from openings 20^a in a valve seat 20^b and to prevent backflow of oil from chamber 17. A check-valve 25 is applied to the discharge connection from chamber 17 and a pipe 26 is connected to deliver the oil forced past said check-valve to the engine.

A head 27 is slidably mounted in a guide frame 10 and carries a roller 28 on a pin 29 fixed in the head. A cam 30, formed on a sleeve 31 which is fixed to rotate with shaft 11, is adapted to impart the pumping-stroke to the pump-plunger 14. The inner end of the plunger 14 bears against the outer end of the slideable head 27 and is yieldingly held in engagement therewith by the spring 15. A rod 33, which is slidably mounted in the casing 12, is adjustably connected by a screw-thread and nut 34 to a head 35 which is slidably mounted in a guide 36 suitably connected to the frame 10. A pin 37, fixed in said head, carries a roller 38 which is adapted to bear against a cam 39 on the sleeve 31 which rotates with the shaft 11. Said cam and head serve to impart the opening stroke to the suction valve. A spring 40 is applied to retract the rod 33 and head 34 and to keep roller 38 against cam 39. The latter is recessed, as at 39', to permit the suction-valve 18 to remain closed during the full pumping stroke of the plunger 14 under control of the governor mechanism hereinafter set forth.

A receptacle 21 is secured to the casing 12 and the oil supply tank is connected to the bottom of this trap by a pipe 22. The delivery pipe 22 is usually connected to an auxiliary reservoir which will cause a pre-

determined level of oil to be maintained in the receptacle 21. A pet cock 21^a is connected to receptacle 21 so that, in initially filling it, air can be discharged until an oil column of a predetermined height, corresponding to the level of the cock has been established. When this has been done, the pet-cock is closed. A pipe 23, having an opening in communication with the inlet 24 to the suction valve, extends downwardly from the top of receptacle 21 to a point below the oil level. The oil that is not expelled by the pump during a pumping-stroke is passed back through the suction-valve and into receptacle 21, and this air-cushion permits this to be done, it being understood that the oil line between the cup and the auxiliary reservoir is free from obstructions to permit this operation. The purpose of this air-cushion is to destroy the inertia of the line of oil between the supply tank and the suction-valve. The movement of the oil is very rapid and, if it were not for the air in the upper portion of the receptacle 21, which allows a quick relief for the surplus oil, the latter would still be pumped to the engine due to inertia of oil in the pipes from the tank to the trap.

The governor mechanism, for varying the period during which the suction valves will remain open, comprises a cam 41, which is provided with a recess or depression 42, which is adapted to act in conjunction with the recess 39' of cam 39 to lengthen or shorten the period of time during which the suction-valve remains open during the pumping-stroke of plunger 14 to automatically control the amount of fuel delivered to the engine and so as to maintain constancy in the revolutions per minute of the engine. Cam 41 is formed on a hub 43 which is rotatably held on sleeve 44 which is fixed to shaft 11, underlies cam 39 which opens the suction valve, and has its operative edge arranged to contact with a portion of the roller 38 on the head 35 for operating the suction-valve.

Governor arms 45 are pivoted at 46 on a flange 47 on a sleeve 44. These arms act as weights which, under the influence of centrifugal force, operate the cam 41, being connected thereto by links 48 which are pivoted to the distal ends of said arms and to studs 49 which are fixed to the hub 43 of cam 41 and extend through flange 50 on the hub 43. Springs 51 are connected to the lower ends of the studs 49 to normally pull the arms 45 inwardly, the outer ends of these springs being connected at 52 to levers 53 which are pivoted, at 54, to the underside of flange 47 of sleeve 44. When the engine is at rest, the depressions in cams 39 and 41 are coincident. As the speed of the engine increases, the governor weights will move outwardly under the influence of

centrifugal force and will rotate the cam 41 relatively to the cam 39 so that the suction valve will remain open during a shorter period of time during the compression-stroke of the plunger 14. Upon reverse movement of the governor arms, the cam 41 will be reversely rotated to correspondingly increase the period during which the suction-valve will be permitted to remain closed. In this manner, the governor arms, under the influence of centrifugal force controlled by the speed of the engine, will rotate cam 41 relatively to cam 39 so as to vary the length of the cam-depression left by the normally coincident depressions in said cams and thus regulate the period of time during which the suction-valve 20 will remain open during the compression stroke of plunger 14, so that the amount of fuel necessary to maintain a constant engine speed will be delivered to the engine cylinder. In this mechanism, the governor does not shift the valve-opening cam 39 and thus a reactive load on the governor is avoided and it sensitively and accurately controls the suction valve and the speed of the engine.

Mechanism is provided for varying the tension of springs 51 to change the speed of the engine at will while it is running. In practice, it is desired, in some instances, to synchronize the operation of parallel units in the production of alternating current and this mechanism makes it possible to effect speed changes by varying the tension of the springs on the governor. For this purpose, each lever 53 is provided with an abutment 56 which is engaged by a radially extending pin 57 which is slidably mounted in the shaft 11 and the sleeve 44. A rod 58, which is axially slidable in the shaft 11, is provided at its lower end with a control cam-surface 59 which is adapted to adjust the radial pins 57 to shift the levers 53 and thus vary the tension of the governor-springs 51. Speed regulation in this manner does not affect the capacity of the engine for work, because the speed change is not obtained by limiting the amount of fuel-oil delivered to the engine, the changing of the tension on the governor-springs merely causing the engine to revolve at a higher speed, in order to throw out the governor weights before they will curtail the volume of fuel-oil injected into the engine. Any suitable mechanism may be employed for adjusting the rod 58. A collar 60 is connected to the upper end of said rod and provided with trunnions 61 which are suitably connected to an adjusting lever 62 which is pivoted in a bracket 63 secured to the top of the frame 10 and which is provided with a suitable locking device for holding it in adjusted position.

A hub 68 is rotatably held in a bearing 130

69 formed in the top of the frame 10 and is provided with cams 70 which are adapted to engage the slides 27 which operate the pumps, as shown in Fig. 7. A bushing 71 is provided between the hub 68 and the shaft 11. A suitable lever 72 is clamped to the upper end of the hub 68 so that the cams 70 may be rotated to simultaneously operate all of the pumps. This mechanism exemplifies a construction in which the cams for all of the cylinders are mounted on a common hub around the governor shaft and whereby all of the pump-plungers may be simultaneously operated. In starting the engine, the engine-shaft will be turned to the point where the depressions in cams 39 will permit one of the suction-valves to close. The pumps may then be operated manually by lever 72 and cams 70 until a solid stream of oil issues from the usual try-cock on the inspirator.

Each head 27 is provided with an opening 75 to receive a key 76 whereby it may be locked in inoperative position. By means of this key, one of the heads 27 may be secured in inoperative position to render one pump-cylinder inoperative which is sometimes desirable, for example when the engine is used for pumping air to a storage tank.

The invention exemplifies a governing mechanism for oil engines in which a cam is provided for regulating the period of time during which the suction-valve is held open, which imposes no reactive load on the governor, such load being imposed upon the positively driven cam which opens the suction valve. The invention also exemplifies a device for destroying the inertia of the line of oil between the suction-valve and the supply tank. Also mechanism for adjusting the tension of the governor springs while the engine is in operation without affecting the working capacity of the engine or without limiting, in a permanent degree, the amount of fuel-oil delivered to the engine. Also simple mechanism for simultaneously and manually shifting the pump-plungers.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In governing mechanism for oil engines, the combination of a pump for feeding oil to the cylinder, a spring closed suction valve for controlling the volume of oil forced into the cylinder, mechanism for operating the pump, mechanism comprising a positively driven cam for opening the valve, a controller-cam coaxial with the cam for

opening the valve, and a governor connected to operate the controller cam, to control the periods during which the valve remains open during the pumping strokes.

2. In governing mechanism for oil engines, the combination of a pump for feeding oil to the cylinder, a suction valve for controlling the volume of oil forced into the cylinder, mechanism for operating the pump, valve controlling means comprising a plurality of cams, and a governor connected to shift one cam relatively to the other to control the periods during which the valve remains open during the pumping strokes, said cams being coaxial and having coincident concentric portions to operate the valve, without imposing a reactive load on the governor.

3. In governing mechanism for oil engines, the combination of a pump for feeding oil to the cylinder, a suction valve for controlling the volume of oil forced to the cylinder by the pump, cams for operating the pump and opening the valve positively driven by the engine, a governor for controlling the period of time during which the suction valve remains open during the pumping stroke, and a cam separate from the cams for operating the pump and opening the valve and shifted relatively to the suction-valve cam by said governor.

4. In governing mechanism for oil engines, the combination of a pump for feeding oil to the cylinder, a suction valve for controlling the volume of oil forced to the engine by the pump, a shaft geared to be driven by the engine, cams fixed on said shaft for operating the pump and opening the suction valve, a centrifugal governor also mounted on said shaft and a supplemental cam for controlling the closing of the suction valve, rotatively mounted around the shaft and operated by said governor.

5. In governing mechanism for oil engines, the combination of a pump for feeding oil to the cylinder, a spring-closed suction-valve for controlling the volume of oil forced to the engine by the pump, a shaft geared to be driven by the engine, cams fixed on said shaft for operating the pump and opening the suction valve, a centrifugal governor also mounted on said shaft and a cam operated by the governor for controlling the closing of the suction-valve rotatively mounted around the shaft and in contiguous relation to the valve-opening cam.

6. In governing mechanism for oil engines, the combination of a drive-shaft, a pump for feeding oil to the cylinder, a suction-valve for controlling the volume of oil forced to the engine by the pump, cams fixed to the drive-shaft for operating the pump and valve, a governor, a cam rotatable on the shaft for controlling the period of time during which the suction-valve remains open

during the pumping stroke, the governor comprising an arm connected to operate said cam, a spring applied to retract said arm, a lever to which the spring is connected, and 5 means adapted to be adjusted while the engine is running to shift the lever to vary the tension of the spring comprising a rod 10 slideable in said shaft.

7. In governing mechanism for oil engines, the combination of a pump for feeding oil to the cylinder, a suction-valve for controlling the volume of oil forced to the engine, a shaft geared to the engine, cams on the shaft for operating the pump and 15 opening the suction valve, a cam for controlling the period of time during which the suction valve remains open, a governor comprising arms, springs for retracting the arms, levers to which the springs are connected, pins mounted in the shaft for shifting said levers and a rod in said shaft for shifting the pins to adjust said levers and 20 vary the tension of the spring.

8. In governing mechanism for oil engines, the combination of a plurality of 25

pumps for feeding oil to the cylinders, suction valves for controlling the volume of oil forced to the cylinders respectively, means for operating the pumps and opening the valves, a governor for controlling the period 30 of time during which the suction valves remain open during the pumping strokes, a plurality of cams to shift the pump-plungers, and a lever for simultaneously operating said cams.

9. In governing mechanism for oil engines, the combination of a plurality of pumps for feeding oil to the cylinders, suction valves for controlling the volume of oil forced to the cylinders respectively, a shaft 40 geared to the engine, cams on the shaft for operating the pump and opening the valve, a governor for controlling the period of time during which the suction valves remain open during the pumping strokes, a plurality of 45 cams rotatable around the shaft and adapted to shift the pump-plungers, and a lever for simultaneously rotating said cams.

F. W. SEVERIN.
